UNITED STATES PATENT OFFICE.

ALBERT H. HOUSE AND OSMOND W. OLMSTED, OF WINDSOR, AND WILLIAM L. GUMPRECHT, OF HARTFORD, CONNECTICUT, ASSIGNEES TO THE AUTO EQUIPMENT COMPANY, OF HARTFORD, CONNECTICUT, A CORPORATION OF CONNECTICUT.

DESIGN FOR AN AUTOMOBILE-INDICATOR.

50,418.

Specification for Design.

Patented Mar. 6, 1917.

Application filed April 18, 1916. Serial No. 92,045. Term of patent 14 years.

To all whom it may concern:

Be it known that we, ALBERT H. HOUSE, a citizen of the United States, and a resident of Windsor, in the county of Hartford and State of Connecticut, OSMOND W. OLMSTED, a citizen of the United States, and a resident of said Windsor, Connecticut, and WILLIAM L. GUMPRECHT, a subject of the King of Great Britain, and a resident of Hartford, in said county and State, have invented a new, original, and ornamental Design for Automobile-Indicators, of which

the following is a specification, reference being had to the accompanying drawing, forming part hereof.

The figure is a perspective view of an automobile indicator showing our new design.

We claim:

The ornamental design for an automobile indicator as shown.

ALBERT H. HOUSE.
OSMOND W. OLMSTED,
WILLIAM L. GUMPRECHT.
